ABSTRACT OF THE DISCLOSURE

The guide arms pivotally mounts a rear saddle which in turn pivotally mounts the front saddle. The central pressure roller is adjustably mounted in the front saddle while the rear pressure roller is adjustably mounted in the rear saddle. Also, the central pressure roller and rear pressure roller are mounted in planes which intersect each other to form an enclosed acute angle thereby allowing a wide range of adjustment for long and short staple fibers.

This invention relates to an adjustable textile drafting apparatus for flyer and speed frames and spinning machines. More particularly, this invention relates to the mounting of the top pressure rollers in a pivotal guide arm or weighing arm.

Heretofore, textile drafting arrangements have been known wherein three pressure rollers which press against corresponding drive rollers have been adjustably mounted to vary the spacing between each adjacent pressure roller. Generally, in order to permit adjustment in spacing, the pressure rollers have been secured in suitable holders or bearings which have been adjustably mounted in saddles on a guide arm above the drive rollers. In some instances, a pair of saddles have been used to mount the three pressure rollers. In such instances, one saddle is pivotally supported in the guide arm and the rear pressure roller holder is displaceably secured within a rearwardly-extending lever arm of the saddle. Also, a second saddle is pivotally supported in a forwardly-extending lever arm of the first saddle to receive the other two pressure rollers. The forward pressure roller holder is mounted in a front portion of the second saddle and the central pressure roller holder is mounted in a rear portion of the second saddle.

However, while the pressure rollers or the various holders in this arrangement can be mutually adjusted in order to vary the spacing therebetween, the holder for the central pressure roller is disposed to be displaceable in a plane parallel to the plane of the drafting field.

Further, because of the adjustability of the pressure rollers, the nip spacing of the main drafting zone can be adapted to the "staple diagram" of the fiber material of the material to be spun. However, in order to be able to adjust the length of the pre-drafting field so that it also corresponds to the staple, the holder for the draw-in pressure roller is also arranged to be adjustably fixed within a guideway extending in a plane parallel to the drafting field.

2

Because of the mounting of the central pressure roller and draw-in pressure roller in the above manner, a disadvantage has resulted in the case of the required guide arms on drafting arrangements which have been adjustable for long staple fibers. That is, the holder for the draw-in pressure roller of the pre-drafting field can only be brought up to the guideway for the holder of the central pressure roller after shortening of the main drafting field to a space for short staple fibers. However, because of the long guideway necessary for long staple fibers for the holder of the central pressure roller, the distance between the draw-in pressure roller and the central pressure roller cannot be further diminished and consequently not adjusted to a measure required for short staple fibers.

Also, in those known devices where the guideways are positioned parallel to each other and the guideway for the holder of the draw-in pressure roller is positioned at a higher level than the guideway for the holder of the central pressure roller, the holder for the draw-in pressure roller can only be brought up to the guideway for the holder of the central pressure roller. Thus, after shortening of the distance in the main drafting field, a corresponding shortening of the distance in the pre-drafting field cannot take place since a further moving of the holder of the draw-in roller towards the holder of the central pressure roller is impaired by the guideway for the latter.

Accordingly, it is an object of the invention to adjust the spacing between the pressure rollers of a drafting apparatus within a wide adjustment range and within a close adjustment range.

It is another object of the invention to mount the pressure rollers of a drafting apparatus in a manner to permit an adjustment for drafting short staple or long staple.

It is another object of the invention to permit adjustment of the draw-in pressure roller without interference from the central pressure roller.

Briefly, the invention provides a drafting arrangement wherein a single guide arm mounts a pair of saddles for pivotal movement with respect to each other. The rear saddle is pivotally mounted in the guide arm and mounts a rear draw-in roller holder whereas the front saddle is pivotally mounted in the front saddle and mounts a front pressure roller holder and a central pressure roller holder. Also, the rear draw-in roller holder is mounted in an adjustable manner within a guide slot of the rear saddle while the central pressure roller holder is similarly mounted in a guide slot of the front saddle which is disposed in a plane different from the plane of the rear saddle guide slot.

In one embodiment of the invention, the projected plane of the guide slot for the central pressure roller planes of the respective guide slots intersect each other with the plane of the guide slot for the central pressure roller directed upwardly towards the guide slot of the rear saddle.

In either embodiment, the holder for the rear draw-in pressure roller is adjustable for narrow or close adjustment below the guide slot for the central pressure roller holder. Thus, the pressure rollers can be adjusted both to short and long staple lengths. Also, it is possible to use the same pressure roller holder both for the draw-in holder and the central pressure roller.

These and other objects and advantages of the invention will become more apparent from the following detailed

description and appended claims taken in conjunction with the accompanying drawings in which:

FIG. 1 illustrates a longitudinal cross-sectional view through a drafting apparatus of the invention arranged for short staple lengths;

FIG. 2 illustrates a view similar to FIG. 1 of the drafting apparatus arranged for long staple lengths; and

FIG. 3 illustrates a view taken on line III—III of FIG. 2.

Referring to FIGS. 1 to 3, the drafting apparatus includes a guide arm 1 which is pivotally mounted on a machine frame about a pivot 2. Similarly, a lever 3 is pivotally mounted in a stationary housing of the machine frame about a pivot 2' for applying a pressure force from a compression spring means 4 onto a closure lever 5 (FIG. 1) and, via the lever 5, on the guide arm 1. The closure lever 5 is pivotally mounted on the guide arm 1 by a pin 6 which passes through the guide arm 1. The pin 6 is disposed, as shown, above the point 3' at which the lever 3 acts on the closure lever 5 to bias the closure lever 5 in a counterclockwise direction as viewed in FIG. 1.

The guide arm 1 is constructed with a pair of depending lateral cheeks 8, each of which includes a plurality of aligned bores. The cheeks 8 support a pin 7 which passes through an opposed pair of bores while the pin 7 serves as a pivot axis to pivotally mount a rear saddle 9 within the cheeks 8. The rear saddle 9 includes a plurality of aligned horizontal bores for selectively receiving the pin 7. By inserting the pin 7 through selected pairs of aligned bores in the cheeks 8 and the rear saddle 9, the pivot point of the rear saddle 9 relative to the guide arm 1 and lever arm ratio can be changed without changing the position of the saddle 9 relative to the guide arm 1. A U-shaped tumbler roller holder 14 having a pair of depending lateral lugs 13 (FIG. 3) overlies the guide arm 1 and pin 7 in order to prevent unintentional lateral sliding of the pin 7 out of the bores in the guide arm 1.

The forward portion of the rear saddle 9 is U-shaped in cross-section while the rear portion is box-shaped in cross-section and includes a guide slot 10 in the lower wall for receiving a rear draw-in holder 12 of a rear draw-in pressure roller 12'. The rear holder 12 is constructed so as to be adjusted and locked within the slot 10, for example, through means of a screw and nut connection 11. Additionally, the rear portion of the rear saddle 9 has a second row of bores below the row of bores for the pin 7. This second row of bores are sized to receive a pin 15 (FIG. 3) which serves as a bearing and pivot axis for a front saddle 16.

The front saddle 16 has a front lever end which is provided with a row of bores to receive the pin 15 and which carries a holder 17, as above, for a front pressure roller 17' and a rear lever arm which carries a holder 18 for a central pressure roller 18'. The rear lever arm includes a guide slot 19 in which the holder 18 is adjusted and locked in place by a screw and nut connection as above. The guide slot 19 is disposed in a plane which intersects the plane of the guide slot 10 in the rear saddle so as to form an enclosed acute angle therewith. In this regard, the plane of the guide slot 19 slopes upwardly and towards the guide slot 10, as viewed.

Referring to FIG. 1, in order to draft short staple lengths of fibers, the pin 7 is placed in a forward set of bores at the free end of the guide arm 1 as well as in a forward set of bores of the rear saddle 9. Also, the pin 15 is placed in a forward set of bores in the forward portion of the rear saddle 9 and front saddle 16. Further, the holders 12, 18 for the rear draw-in pressure roller 12' and central pressure roller 18' are moved into the foremost ends of the respective guide slots 10, 19 and locked in place. The guide arm 1 is then pivoted in counterclockwise manner under the bias of the spring means 4 to cause the pressure rollers 12', 17', 18' to press against the respective drive or draw-off rollers 20, 21, 22. In this position, the guide

slot 19 of the holder 18 of the central pressure roller 18 extends at an angle relative to the guide slot 10 for the rear draw-in holder 12 such that the planes of the respective guide slots 19, 10 intersect and the holder 12 is positioned beneath the guide slot 19.

Referring to FIG. 2, in order to draft long staple lengths of fibers, the pin 7 is placed in a rear set of bores of the guide arm 1 and rear saddle 9. Also, the pin 15 is placed in a rear set of bores in the forward portion of the rear saddle 9 and front saddle 15. Finally, the holders 12, 18 are moved into the rearmost ends of the respective guide slots 10, 19 and locked in place.

What is claimed is:

1. A drafting apparatus for textile machines comprising a guide arm,

a rear saddle pivotally mounted in said guide arm and including a first guideway at the rear thereof for adjustably receiving a draw-in pressure roller therein, a front saddle pivotally mounted in the front of said rear saddle, said front saddle including a second guideway at the rear thereof for adjustably receiving a central pressure roller therein and means at the front thereof for receiving a front pressure roller, said second guideway being disposed in a plane different from the plane of said first guideway, and a pin pivotally mounting said rear saddle in said guide arm, and a plurality of bores in said rear saddle and a plurality of bores in said guide arm for selectively receiving said pin to vary the pivot axis of said rear saddle.

2. A drafting apparatus for textile machines comprising a guide arm,

a rear saddle pivotally mounted in said guide arm and including a first guideway at the rear thereof for adjustably receiving a draw-in pressure roller therein,

a front saddle pivotally mounted in the front of said rear saddle, said front saddle including a second guideway at the rear thereof for adjustably receiving a central pressure roller therein and means at the front thereof for receiving a front pressure roller, said second guideway being disposed in a plane different from the plane of said first guideway, and a pin pivotally mounting said front saddle in said rear saddle and a plurality of bores in said rear saddle and a plurality of bores in said front saddle for selectively receiving said pin to vary the pivot axis of said front saddle longitudinally of said front saddle.

3. A drafting apparatus for textile machines comprising a guide arm,

a rear saddle pivotally mounted in said guide arm and including a first guideway at the rear thereof for adjustably receiving a draw-in pressure roller therein, a front saddle pivotally mounted in the front of said rear saddle, said front saddle including a second guideway at the rear thereof for adjustably receiving a central pressure roller therein and means at the front thereof for receiving a front pressure roller, said second guideway being disposed in a plane different from the plane of said first guideway and terminating at the rear end thereof in front of the front end of said first guideway, said plane of said second guideway being directed upwardly towards said plane of said first guideway, said second guideway being pivotally mounted to pass through the projected plane of said first guideway.

4. An apparatus as set forth in claim 3 further comprising a holder adjustably mounted in said first guideway for mounting the draw-in pressure roller, said holder being adjustable to a position beneath said second guideway.

5. A drafting apparatus as set forth in claim 3 wherein the plane of said second guideway encloses an acute angle with the projected plane of said first guideway.

6. A drafting apparatus as set forth in claim 5 wherein the plane of said second guide way intersects said projected plane of said first guide way in front of said first guide way.
